US00D999374S

(12) **United States Design Patent** (10) **Patent No.:** **US D999,374 S**
Chen et al. (45) **Date of Patent:** **** Sep. 19, 2023**

(54) **SURGICAL SHEATH**

(71) Applicant: **SPIWay LLC**, Carlsbad, CA (US)

(72) Inventors: **Eugene Chen**, Carlsbad, CA (US);
Richard C. Ewers, Carlsbad, CA (US);
Cang Lam, Irvine, CA (US); **Stephanie Frimond**, Carlsbad, CA (US)

(73) Assignee: **SPIWAY LLC**, Carlsbad, CA (US)

(**) Term: **15 Years**

(21) Appl. No.: **29/826,069**

(22) Filed: **Feb. 9, 2022**

Related U.S. Application Data

(63) Continuation of application No. 29/672,583, filed on Dec. 6, 2018, now abandoned, which is a continuation-in-part of application No. 15/680,947, filed on Aug. 18, 2017, now abandoned, which is a continuation-in-part of application No. 15/340,718, filed on Nov. 1, 2016, now Pat. No. 9,949,621, which is a continuation of application No. 14/626,184, filed on Feb. 19, 2015, now abandoned, which is a continuation of application No. 13/798,990, filed on Mar. 13, 2013, now Pat. No. 8,986,201.
